FÉLIX EMILE VALOIS, OF BRIDGEPORT, CONNECTICUT, ASSIGNOR TO HAMEL SHOE MACHINERY COMPANY, OF LYNN, MASSACHUSETTS, A CORPORATION OF MASSACHUSETTS.

NEEDLE-MOTION.

1,368,418.

Specification of Letters Patent. Patented Feb. 15, 1921.

Application filed August 1, 1918, Serial No. 247,752. Renewed July 8, 1920. Serial No. 394,807.

To all whom it may concern:

Be it known that I, FÉLIX EMILE VALOIS, a citizen of the United States, residing at Bridgeport, county of Fairfield, State of Connecticut, have invented a certain new and useful Improvement in Needle-Motions, of which the following is a specification, reference being had therein to the accompanying drawings.

10 My invention relates to sewing machines having a curved hook needle of the kind ordinarily employed in the manufacture of boots and shoes. The invention has to do particularly with the needle actuating mechanism or needle drive for such a machine.

15 The particular object of the invention is to provide a needle drive which shall permit the machine to be run at high speed and to operate without unnecessary vibration or jar. 20 It has for a further object to provide a needle drive in which no cams, racks or pinions are employed and which will therefore have greater durability as well as greater smoothness of operation. A further object of the 25 invention is to give to the needle certain variations in angular velocity which will produce more perfect coöperation with the other stitch forming instrumentalities.

30 All of the foregoing objects are accomplished by my invention and the machine embodying it is simple, economical to manufacture and effective in its operation. It may be run at exceedingly high speeds with a minimum of vibration and noise.

35 In the accompanying drawings only those parts of the machine which relate directly to the needle drive are shown since the remainder of the machine forms no part of my present invention.

40 The invention will be fully understood from the following description when taken in connection with the accompanying drawings and the novel features thereof will be pointed out and clearly defined in the claims 45 at the close of this specification.

In the drawings, Figure 1 is a side elevation of the parts of a needle drive of a sewing machine embodying my invention.

45 Figs. 2, 3 and 4 are similar views showing successive positions of the needle drive.

50 Fig. 5 is a top plan view of the parts shown in Fig. 1.

Fig. 6 is a diagram illustrating the movement of the needle.

Referring now to the drawings, at A and B 55 are shown parts of the frame of the machine. At 11 is shown a curved hook needle of the usual form. At 13 is shown the work support or table. The needle 11 is mounted on a needle sector 12 pivoted on the needle shaft 60 14 so that the needle sector and the needle are capable of being oscillated about the needle shaft in proper relation with the other stitch forming instrumentalities among which is a shuttle 15.

65 At 16 is shown the main shaft of the machine. This main shaft revolves with uniform angular velocity and is actuated by mechanism which is not shown. On the main shaft 16 is a crank 17 having a relatively 70 large crank pin 18. The crank revolves about the main axle 16 in the direction of the arrow in Fig. 1. On the crank pin 18, is a connecting rod 19 of skeleton shape as shown, the free end of which is pivoted at 20 75 to the upper end of an L-shaped link 21 the other end of which is pivoted at 22 to the needle sector at one side of the crank. The movement of the connecting rod 19 is in part controlled by means of a link or movable fulcrum 23 one end of which is pivoted at 24 80 to a fixed part of the machine farther from the needle sector than shaft 16 and above the same and the other end of which is pivoted at 25 to the connecting rod 19 at a point intermediate the crank pin 18 and pivot 20, and at one side of a straight line passing through the center of the crank pin 18 and the center of the pivot 20.

85 When the needle is at the lowest point of 90 its stroke, the crank 17 will be in the position shown in Fig. 1. The path of the center of the crank pin 18 is indicated in dot and dash line in Fig. 1 on which certain positions have been indicated by letters. The 95 path of the needle will be better understood by comparing the diagram (see Fig. 6) with the positions indicated on the dot and dash circle in Fig. 1. The diagram forming Fig. 6 is a horizontal projection of the point of 100 the needle in its various positions. Let it be assumed that the needle starts at the position shown in Fig. 1. At this time the needle will be at the point indicated by *a* in Fig. 6 and the center of the crank pin 105 in Fig. 6 will be at the position designated *a* in Fig. 1. The crank pin then moves to the position shown in Fig. 2. The center of the crank

- pin will then be at the point *b* (see Fig. 1) and the needle will be at the point *b* in the diagram in Fig. 6. The crank then moves to the position shown at *c* (see Fig. 1) and 5 the needle moves down slightly as indicated at *c* in Fig. 6. Further movement of the crank pin to the position *d* (see Figs. 1 and 4) carries the needle to the position *d* in the diagram which position is above the 10 point *b* therein and is the extreme top position reached by the needle. The travel of the crank pin from *d* to *a* brings the parts back to the starting point this being indicated by *a'* in Fig. 6.
- 15 From the foregoing it will be seen that the needle travels very rapidly during its up stroke and until it reaches the point *b*. (See Figs. 2 and 6). The needle then remains practically stationary but having a 20 slight dip from *b* to *c*, sufficient to loosen the thread from the barb of the needle, while the crank travels to the point *d* at which time the needle is slightly higher and farther back out of the way than it was at the point *b*. The down stroke from the point *d* to a 25 point opposite the point *c* is very slow at first after which the rapidity of movement of the needle increases suddenly until the extreme bottom position is reached.
- 30 The needle practically rests or dwells at a point near the top of its stroke while the crank moves through an angle of about 40 degrees and then moves up and back out of the way of the shuttle to clear the thread to 35 allow the shuttle to pick the loop up from the needle and to give the shuttle time to pass through the loop and the needle to get back out of the way of the shuttle.
- In spite of the rapidity of movement 40 given to the needle, and the long rest or pause, the machine runs very smoothly and quietly owing to the fact the needle drive contains no cams or racks.
- 45 What I claim is:
1. In a sewing machine, the combination of an oscillatable needle sector, a crank, a connecting rod, connections between the needle sector and the connecting rod, and a movable fulcrum connected to the connecting rod at a point intermediate of its ends 50 said parts being so related that said sector has a substantial dwell near one limit only of its motion.
  2. In a sewing machine, the combination of a crank, a connecting rod one end of which is attached to the crank, a needle sector actuated by the other end of the rod, and

a movable fulcrum acting on the connecting rod at a point between the ends of the connecting rod said parts being so related that 60 the needle is caused to dip near one limit of its stroke.

3. In a sewing machine, the combination of a crank, a connecting rod one end of which is pivoted on said crank, a needle sector pivotally connected to the other end of said rod, and a link forming a movable fulcrum, one end of said link being connected to the connecting rod at a point between the ends thereof and at one side of a line connecting its pivotal connections, and the other end of said link being pivotally supported. 65

4. In a sewing machine, the combination of a drive shaft, a crank thereon, a connecting rod one end of which is attached to said 70 crank, a link pivoted at one end at a fixed point above said crank and at the other end to an intermediate point of said connecting rod, an oscillatable needle sector mounted at one side of said crank, and connections from 75 said sector to the other end of said rod.

5. In a sewing machine, the combination of a crank, a connecting rod, an oscillatable needle sector, connections between said rod and said sector, and a link forming a movable fulcrum one end being pivoted to said 80 rod and the other end pivoted at a fixed point at a distance from said sector not less than that of the center of rotation of said crank. 85

6. In a sewing machine, the combination of a crank, a connecting rod one end of which is attached to the crank, an oscillatable needle sector, a link connecting the free end of the connecting rod with the needle sector, and a link one end of which is pivoted to a fixed part of the machine and the other is pivoted to the connecting rod at a point intermediate its ends. 90

7. In a sewing machine, the combination 100 of a crank, a connecting rod one end of which is attached to the crank, an oscillatable needle sector, a link connecting the free end of the connecting rod with the needle sector, and a link one end of which is 105 pivoted to a fixed part of the machine and the other is pivoted to the connecting rod at a point intermediate its ends and at one side of the line connecting the center of the crank pin with the pivot at the other end of 110 the connecting rod.

In testimony whereof I affix my signature.

FÉLIX EMILE VALOIS.
